Primary Examiner—Adir Aronovich(74) *Attorney, Agent, or Firm*—Foley & Lardner**(57) CLAIM**

The ornamental design for an electronic control apparatus, as shown and described.

DESCRIPTION

FIG. 1 is a perspective view of an electronic control apparatus;

FIG. 2 is a left side elevation view thereof;

FIG. 3 is a top plan view thereof;

FIG. 4 is a front elevation view thereof;

FIG. 5 is a bottom plan view thereof;

FIG. 6 is a right side elevation view thereof;

FIG. 7 is a back elevation view thereof;

FIG. 8 is a perspective view of a first alternate arrangement for our electronic control apparatus;

FIG. 9 is a right side elevation view thereof, wherein the left side elevational view is a mirror image of the right side elevation view and the top, front, bottom and back views are the same as those shown in FIGS. 3, 4, 5 and 7, respectively;

FIG. 10 is a perspective view of a second alternate arrangement for our electronic control apparatus;

FIG. 11 is a left side elevation view thereof;

FIG. 12 is a top plan view thereof;

FIG. 13 is a bottom plan view thereof; and,

FIG. 14 is a right side elevation view thereof, wherein the front and back views are the same as those shown in FIGS. 4 and 7, respectively.
